UNITED STATES PATENT OFFICE.

GEORGE F. HUTCHINS, OF WORCESTER, MASSACHUSETTS, ASSIGNOR TO UNIVERSAL SAFETY TREAD COMPANY, OF JERSEY CITY, NEW JERSEY, AND PROVIDENCE, RHODE ISLAND, A CORPORATION OF NEW JERSEY.

ROLLING-MACHINE FOR FORMING LIPS ON TREADS, &c.

SPECIFICATION forming part of Letters Patent No. 730,019, dated June 2, 1903

Application filed July 19, 1902. Serial No. 116,229. (No model.)

To all whom it may concern:

Be it known that I, GEORGE F. HUTCHINS, a citizen of the United States, residing at Worcester, in the county of Worcester and State of Massachusetts, have invented certain new and useful Improvements in Rolling-Machines for Forming Lips on Treads, &c., of which the following is a specification, reference being had therein to the accompanying drawings.

The object of my invention is to produce a machine through which non-slipping or safety tread—such, for example, as that described in United States Letters Patent No. 638,666, of December 5, 1899—(or other suitable material) may be passed and during the passage guided properly so as to form a curved lip or “nosing” along one margin of the sheet-metal portion of the tread, the nosing being parallel with the ribs and projecting in the opposite direction from the ribs.

Figure 1 is a side elevation of one form of machine embodying my present invention. Fig. 2 is a side elevation, partly in section, of the tread-guiding and lip-bending rolls. This view also shows the gearing of the rolls in side elevation. Fig. 3 is a cross-sectional view at line 3-3 of Fig. 1. Fig. 4 is an edge view of a section of a so-called “safety” tread provided with a curved lip or nosing at one margin.

In the drawings illustrating my invention, A and B are two rolls mounted in suitable supports A' A' and driven in any suitable manner—for example, by gearings such as shown—and the arrangement and mode of operation of which will be readily understood by all mechanics without particular description. One of the rolls, as A, is formed with alternating circumferential ribs a and grooves a'. Roll B is a plain-surfaced roll and coöperates with roll A. The purpose of the ribs a is to enter the grooves of the material passed through the machine and the purpose of the grooves a' is to receive the ribs which alternate with the grooves in said material.

In Fig. 4, x represents the ribs of the material passed through the machine, and x' represents the grooves of said material. It is plain, therefore, that when the material is

passed through the machine between the rolls A and B the sheet material will be held and guided by the coöperation of the rolls and by the coöperation of the ribs a and grooves a' with the ribs x and grooves x'. Roll B is a plain-surfaced roll. One end portion of roll A is formed with a concave circumferential shoulder a², the wall surface whereof curves upwardly and outwardly, so that the greater portion of the shoulder projects beyond the surfaces of the ribs a. Shoulder a² runs into the enlarged end portion a³ of roll A, the surface of which is parallel with the lengthwise axis of roll A. Shoulder a² overhangs the rounded end portion b of roll B and when the material is passed between the rolls a free margin of the sheet-metal portion of the work is curved downwardly between the opposed concave wall or shoulder a² and the convex or rounded end portion b of roll B, so that the nosing or lip x² is formed. Roll B outwardly from convex shoulder b is preferably formed with a circumferential shoulder b', which is opposite the shoulder a². If desired and the margin of the sheet material is wide enough, that margin may be formed with a nosing which will run into a straight portion of the margin and will pass between the shoulders a² and b'.

When the material is passed between the rolls, it has a tendency to curl downwardly, and to overcome this I prefer to provide the machine with a roll D, mounted in bracket-arms d and holding roll D parallel with roll B, so that the under surface of the stock as it comes from between the rolls A and B will be supported by the roll D. It is desirable that the roll D should have what may be called “lateral” as distinguished from “endwise” adjustment, so that its upper or contact surfaces may be raised or lowered with relation to the uppermost line of the roll B. To this end the bracket-arms d are carried by an adjustable bar D', which is provided with elongated openings d', through which fasteners d² pass into the inclined support d³ for said bar D'. By this construction the bar D' may be slid edgewise on the support d³, thereby carrying the roll D upwardly or downwardly in relation to the roll B. Some stock is liable to

curl more than others, and it is particularly desirable that the roll D should be adjustable, as stated.

The support d^3 is formed with a lateral base portion d^4 , which is clamped or otherwise suitably secured on the beds d^5 of the machine. From the forward edge of support d^3 there are upturned projections d^6 , through which adjusting-screws d^7 are passed, the lower ends of the adjusting-screws impinging against the bed d^5 , so that by loosening the fasteners d^8 of the base d^4 and adjusting the screws d^7 a further adjustment of roll D in relation to roll B is obtained, as will be plain from the drawings without more particular description.

The rolls are made movable one toward the other, so that the extent of the overhang of shoulder a^2 over the rounded end portion b may be increased or diminished to form lips of different widths. To this end roll A is mounted in suitable adjustable boxes f in frame-pieces A' A', separated by springs f' or in any other suitable manner, the adjustment being made by turning screws f^2 .

25 What I claim is—

1. In a rolling-machine for forming lips on treads, the combination of a plain-surfaced under roll; an alternately ribbed and grooved upper roll; intermeshing gears on said rolls; 30 means for supporting said rolls; and a driving-gear on the lower roll; the upper roll hav-

ing a concave wall a^2 , and the under roll having an opposed convex wall, substantially as described.

2. In a rolling-machine for forming lips on 35 treads, the combination of a roll having alternating ribs and grooves and a concave wall at one end; a co-operating roll having a smooth surface and a convex surface at one end, opposed to the concave surface of the other roll; 40 means for supporting said rolls; means for driving them simultaneously; a roll, D, and means for supporting roll D in operative relation to the other rolls.

3. In a rolling-machine for forming lips on 45 treads, the combination of a roll having alternating ribs and grooves and a concave wall at one end; a co-operating roll having a smooth surface and a convex surface at one end, opposed to the concave surface of the other roll; 50 means for supporting said rolls; means for driving them simultaneously; a roll, D; means for supporting roll D in operative relation to the other rolls; and means for moving the roll D toward and from said other rolls.

55 In testimony whereof I affix my signature in presence of two witnesses.

GEORGE F. HUTCHINS.
